(57) **CLAIM**

The ornamental design for a rear combination lamp for motorcycle, as shown and described.

DESCRIPTION

FIG. 1 is a front right perspective view of a rear combination lamp for motorcycle.

FIG. 2 is a front left perspective view thereof.

FIG. 3 is a front elevation view thereof.

FIG. 4 is a right side elevation view thereof; and,

FIG. 5 is a top plan view thereof.

The broken lines shown in the drawings illustrate portions of the rear combination lamp for motorcycle that form no part of the claimed design.
